(57) **CLAIM**

The ornamental design for a laptop computer case, as shown and described.

DESCRIPTION

FIG. 1 is a perspective view (showing the top and front) of a laptop computer case in accordance with our new design (wherein the case is in a folded state);

FIG. 2 is a top view of the case of FIG. 1 (wherein the case is in a folded state);

FIG. 3 is a front view of the case of FIG. 1 (wherein the case is in a folded state);

FIG. 4 is a right-side view of the case of FIG. 1 (wherein the case is in a folded state);

FIG. 5 is a rear view of the case of FIG. 1 (wherein the case is in a folded state);

FIG. 6 is a bottom view of the case of FIG. 1 (wherein the case is in a folded state);

FIG. 7 is a top view of the case of FIG. 1 (wherein the case is in an unfolded state);

FIG. 8 is a front view of the case of FIG. 1 (wherein the case is in an unfolded state);

FIG. 9 is a left-side view of the case of FIG. 1 (wherein the case is in an unfolded state); and,

FIG. 10 is a bottom view of the case of FIG. 1 (wherein the case is in an unfolded state).

A left-side view (not shown) corresponding to the right-side view of FIG. 4 is a mirror image of that shown in FIG. 4 and a right-side view (not shown) corresponding to the left-side view of FIG. 9 is a mirror image of that shown in FIG. 9. The broken lines outlining fastening members (e.g., hook-and-loop fastening members) in FIGS. 3, 4 and 7–10 are for illustrative purposes only and form no part of the claimed design.

The broken lines outlining a computer in FIGS. 8 and 9 are for illustrative purposes only and form no part of the claimed design.
